United States Patent

Des. 238,168

Patented Dec. 23, 1975

238,168

BUILDING BLOCK OR SIMILAR ARTICLE

Henry King Ketcham, Geneva, Switzerland, assignor to
Rolande Ketcham, Geneva, Switzerland

Filed Apr. 26, 1973, Ser. No. 354,669

Term of patent 14 years

Int. Cl. D25—01

U.S. Cl. D18—2 R

Fig. 1

Fig. 4

Fig. 2

Fig. 3

Fig. 5

FIG. 1 is a perspective view of a building block or similar article embodying my new design;

FIG. 2 is an elevational view, the opposite side being the same in appearance as the side shown;

FIG. 3 is an elevational view looking from the left of FIG. 2, the opposite side being the same in appearance as the side shown;

FIG. 4 is a top plan view; and

FIG. 5 is a bottom plan view thereof.

I claim:

The ornamental design for a building block or similar article, as shown and described.
